PULSE ENERGIZED GAS TUBE CIRCUIT

Edward Oscar Johnson, Princeton, N. J., assignor
to Radio Corporation of America, a corporation
of Delaware

Application January 2, 1951, Serial No. 203,951

8 Claims. (Cl. 315—349)

1

This invention relates to improvements in electron gas tube systems, and particularly to an improved system for pulse energizing a gas-filled electron tube of the type wherein the functions of ionization and of principal current delivery are separated.

In a copending application of the present applicant, Serial No. 185,745, filed September 20, 1950, assigned to the assignee of the present invention, there is described a gaseous electron tube wherein ionization is accomplished by passing current between a pair of electrodes in the tube in order to permit large quantities of current to be passed between two other tube electrodes at voltages lower than that required to ionize the gas in the tube. In a copending application of L. Malter, Serial No. 203,923, filed concurrently herewith and assigned to the assignee of the present invention, and in a copending application of I. Wolff, Serial No. 212,632, filed February 23, 1951, and also assigned to the assignee of the present invention, there are described methods and system for operating gas-filled electron tubes by means of pulse voltages.

It is a general object of the present invention to provide an improved apparatus for pulse energization of gas-filled electron tubes.

A more specific object of the invention is the provision of an improved pulse energizing arrangement for gas-filled electron tubes which is adapted to be operated with a voltage source lower than that required to ionize the gas in the tube.

An additional object of the invention is the provision of an improved automatic starting circuit for a pulsed gas tube system.

In accordance with the invention, the foregoing and other related objects and advantages are attained in a system wherein the voltage developed across an inductor by interrupting current flow therethrough is added to the voltage of the current source supplying the inductor in such a way as to provide voltage pulses of amplitude sufficient to ionize the gas in the tube.

A more complete understanding of the invention can be had by referring to the following description of illustrative embodiments thereof, when considered in connection with the accompanying drawing, wherein:

Fig. 1 is a schematic diagram of an electron gas tube system arranged in accordance with the invention.

Figs. 2 and 3 are schematic diagrams of modified forms of the system shown in Fig. 1.

Figs. 4 and 5 illustrate the structure of gas

2

tubes suitable for use in the systems of Figs. 1-3, and

Fig. 6 is a diagram of a further embodiment of the invention.

As is explained in the above-mentioned copending application of the present applicant, it is possible to operate a gas-filled electron tube with low voltages and under readily controlled conditions by providing for an auxiliary discharge current in the tube to generate an ion-electron plasma which will support the main tube current. In general, it is necessary that the auxiliary discharge be established by means of a voltage of amplitude sufficient to ionize the gas in the tube. It has been found, however, that the ionizing discharge need not be a continuous discharge, but that it can be discontinuous or pulsating in nature. In Fig. 1 of the drawing, there is shown a system for deriving ionizing pulses for a gas tube from a voltage source of potential less than that required to ionize the tube gas.

Referring to Fig. 1, there is shown a gas tube 10 having an anode 12, a cathode 14, a control electrode 16, and an auxiliary electrode 18. In the embodiment of the invention presently being described, the auxiliary electrode 18 serves as an auxiliary anode to which electrons will flow from the cathode 14 to ionize the gas in the tube 10. However, as will be shown hereinafter, the auxiliary electrode 18 can as well comprise an electron emitter or cathode with slight modification of the circuit.

The main tube anode 12 is connected to a voltage source, shown as a battery 22, through a load 20. The load 20 may comprise any one of a number of different elements, such as the primary winding of a transformer, a load resistor, or the like. The precise character of the load 20 is not material for present purposes.

The auxiliary electrode 18 also is connected in circuit with the cathode 14 through an inductor 24 and the voltage source 22. A capacitor 26 is connected in parallel with the series combination of the inductor 24 and the voltage source 22. Also, a resistor 28 is connected across the capacitor 26 in series with a switch 30.

Assuming that the voltage of the source 22 is less than that required to ionize the gas in the tube 10, it can be seen that no appreciable current will flow in the tube 10 under static conditions. However, if the switch 30 is closed briefly, current will flow through the inductor 24 and through the resistor 28. If, now, the switch 30 is opened, the effect of suddenly interrupting

the current flowing through the inductor 24 will be to develop across the inductor a voltage substantially equal to that of the source 22. Also, the polarity of this voltage across the inductor 24 will be such as to add to the source voltage, so that the voltage between the cathode 14 and the auxiliary electrode 18 will be approximately twice the voltage of the source 22. If this total voltage between the electrodes 14, 18 is sufficient to ionize the gas in the tube 10, current will flow between the electrodes 14, 18. Also, the ionization produced by this flow of current from the cathode 14 to the electrode 18 will allow current to flow from the cathode 14 to the main anode 12 and through the load 20.

Within a short time after current flows between the electrodes 14, 18, the voltage across the inductor 24 will decrease sufficiently to stop the ionizing current flow between the electrodes 14, 18. However, current will continue to flow through the inductor 24 and into the capacitor 26, thereby setting up an oscillatory action in the inductor-capacitor circuit 24, 26. This will cause the voltage between the electrodes 14, 18 again to build up to the point necessary to ionize the gas in the tube. In this way, a periodic or pulsating current will flow between the electrodes 14, 18, at a frequency determined by the inductance of the inductor 24 and the capacitance of the capacitor 26.

As is explained in the above-mentioned copending Malter application, if the current pulses between the cathode 14 and the electrode 18 are of sufficient intensity and recur rapidly enough, a substantially constant current can be drawn from the cathode 14 to the main anode 12. Furthermore, this current can be modulated by applying a modulating voltage between the control electrode 16 and the cathode 14 through input terminals 32. Thus, it becomes possible to operate the gas tube 10 from a source of voltage lower than that required to ionize the gas in the tube, and to control the tube current by means of an external control voltage.

As was previously stated, the auxiliary electrode 18 in Fig. 1 could as well comprise an auxiliary cathode. An arrangement of this type is shown in Fig. 2.

In Fig. 2 the various elements all correspond with similar elements in the circuit of Fig. 1, with the exception that the auxiliary electrode 18a in the tube 10 is an electron emitter rather than an electron collector. This necessitates a slight change in the circuit configuration. The polarity of the voltage source 22 remains the same so that a positive voltage will be applied between the tube anode 12 and the main cathode 14. However, the auxiliary cathode 18a is returned through the inductor 24 to the negative terminal of the voltage source 22 rather than to the positive terminal as in the circuit of Fig. 1. As in Fig. 1, a capacitor 26 is in shunt with the series combination of the voltage source 22 and the inductor 24. Also, a resistor 28 and a switch 30 are in series across the capacitor 26.

In the circuit of Fig. 2, temporary closing of the switch 30 will establish current flow through the inductor 24 and the limiting resistor 28. When the switch 30 is opened, a voltage will be developed across the inductor 24 which will add to the voltage of the source 22, making the total voltage between the auxiliary cathode 18a and the anode 12 approximately twice the source voltage. Thereupon, current will flow from the auxiliary cathode 18a to the main anode 12, ionizing the

gas in the tube 10. The remainder of the circuit function will be essentially the same as in the circuit of Fig. 1.

Thus far, no consideration has been given to the type of cathode 14 in the tube 10 in Figs. 1 and 2. In the usual case, it is preferable to use a thermionic emitter. This, however, introduces a starting problem. Either it is necessary to provide a separate energization circuit for the cathode heater element, so that the cathode can be heated before main circuit operation is started, or some means is required for supplying circuit interrupting action after the tube cathode has reached operating temperature. In Fig. 3, there is shown a completely automatic starting circuit wherein the closing of a single switch will initiate the desired circuit action.

In the circuit in Fig. 3, the gas tube 10 is provided with a heater element 15 for the cathode 14. This heater element is connected to the voltage source 22 through a switch 34. The cathode 14 is connected to the voltage source 22 through a holding winding 36 of a relay 38. The relay 38 has a second winding 40 which is connected in series between the voltage source 22 and a movable contact 42 of the relay. The circuit for the inductor 24 is completed through the resistor 28 and through the fixed contact 44 of the relay. A spring 41 normally biases the contact 42 against the fixed contact 44.

When the switch 34 is closed, current will begin to flow through the heater 15 to begin heating the cathode 14. Also, current will begin to flow through the inductor 24, the contacts 42, 44, the resistor 28, and the winding 40. Before the heater 15 has warmed up, very little current will flow through the holding winding 36. However, a substantial current will flow through the winding 40, causing the contacts 42, 44 to open. As soon as these contacts open, the current through the winding 40 will be cut off, and the contacts 42, 44 again will close. This action will continue, each time generating sufficient voltage at the auxiliary electrode 18 of the tube 10 to cause an ionizing discharge. However, until the cathode 14 becomes heated no discharge will take place.

As soon as the cathode 14 becomes heated, a current pulse will flow from the cathode 14 to the auxiliary electrode 18. Also, the current will increase through the holding windings 36 as the heater 15 warms up, so that when the cathode 14 becomes fully heated the current through the winding 36 will keep the contacts 42, 44 open. Thereafter, the circuit will operate in substantially the same manner as has already been described for the circuit in Fig. 1.

Although details of tube structure form no part of the present invention per se, for the sake of concreteness there is shown in Fig. 4 a sectional view of a gas tube such as might be used in the circuits of Figs. 1 and 3. In Fig. 5 there is shown a similar view of a tube such as might be used in the circuit of Fig. 2.

The tube shown in Fig. 4 has a gas tight envelope 10, within which there is placed a cathode 14, surrounded by a mesh-type control grid 16 and, outside the grid 16, by an anode 12. An additional electrode 18 is provided adjacent to the cathode 14 to receive ionizing current therefrom. This auxiliary electrode 18 may, for example, comprise two rods disposed on opposite sides of and parallel with the cathode 14.

The tube shown in Fig. 5 comprises a gas tight envelope 10 provided with a cathode 14. A U-shaped control electrode or grid 16 and a U-

5

shaped anode 12 partially surround the cathode 14. The grid 16 comprises a plurality of parallel wires 17 which are supported in spaced relation.

Opposite the open ends of the grid 16 and the anode 12 there is mounted an auxiliary cathode 18a. As is explained in the above-mentioned application of the present applicant, it is advantageous to concentrate the auxiliary cathode ionizing current by surrounding the auxiliary cathode 18a with a cylindrical focusing electrode 19 which has an elongated slot 21 facing the open ends of the grid and anode structures.

Thus far, the present invention has been described with particular reference to gas tubes having electrode structures suitable for grid control of currents drawn through a conductive ion-electron plasma at low voltage drop. Many conventional gas tubes do not have an electrode structure that is suitable for this type of operation. In Fig. 6, there is shown a gas tube circuit in which the principles of the present invention are used to advantage even though no grid control is had of the work circuit current.

The circuit of Fig. 6 includes a gas-filled tube 10a of a commercial type widely known as a "2050 thyratron," taken as typical of many similar conventional gas tubes. The tube 10a has a cathode 14, usually heated by a filament (not shown), a control electrode 13, a so-called shield electrode 12, and an anode 18. In the circuit of Fig. 6, the shield electrode 12 actually serves as an electron collector or anode, and the anode 18 serves as an auxiliary or ionizing electrode. Therefore, these electrodes, 12 and 18, will be referred to herein-after as the anode 12 and the auxiliary electrode 18 to conform with the functions thereof.

As in the circuits of Figs. 1-3, the auxiliary electrode 18 in Fig. 6 is connected to the cathode 14 through an inductor 24 and a voltage source 22. Similarly, a capacitor 26 is connected in shunt with the inductor 24 and the source 22, and a resistor 28 and switch 30 are connected in series across the capacitor 26, as in Figs. 1-3.

The inductor 24 has a dual function in the circuit of Fig. 6. In addition to assisting the development of ionizing pulses as previously described, the inductor 24 acts as the primary winding of a transformer which has a secondary winding 27. The secondary winding 27 is connected in series with a resistor 29 between the anode 12 and the voltage source 2. A filtering capacitor 31 is connected across the resistor 29.

By closing and opening the switch 30, sufficient voltage can be built up between the cathode 14 and the auxiliary electrode 18 to cause pulse ionization as previously described. The pulsating current flowing through the inductor 24 will induce a higher voltage in the secondary winding 27. The anode 12 will cooperate with the cathode 14 to rectify the stepped up voltage appearing across the secondary winding 27, providing a unidirectional voltage across the resistor-capacitor combination 29, 31. This unidirectional voltage can be utilized in any suitable load device 33 connected to a pair of output terminals 35. Thus, the circuit of Fig. 6 will function as a "D.-C. transformer."

The magnitude of the voltage available at the terminals 35 will depend largely on the turns ratio of the transformer 25. An important advantage of the system resides in the fact that there will be substantially no voltage lost between the cathode 14 and the anode 12. As is explained in the above-mentioned Johnson and Malter applications current can be drawn

75 through a conductive plasma in a "separately ionized" gas tube with a voltage drop as low as 0.1 volt.

Due to electrode configuration, the control electrode 13 in the tube 10a will have little control over the work circuit current. This electrode 13 can be left disconnected or "floating," as shown. It should be noted, however, that a mesh-type control electrode surrounding the cathode 14 could be provided for work circuit current control if desired.

From the foregoing, it will be seen that the present invention provides a simple and efficient system for operating a gas-filled tube from a source of voltage less than that required to ionize the tube gas.

What is claimed is:

1. A pulse energizing system for a gas-filled electron tube having a first pair of electrodes for passing ionizing current through the tube and having a second pair of electrodes including at least one electrode in addition to said first pair for passing current through the gas so ionized, a source of voltage of amplitude less than that required to ionize the tube gas, an inductor, a first circuit connecting said inductor to said source to establish current flow through said inductor, a second circuit connecting said inductor and said source between said first pair of electrodes, a circuit connecting said source between said second pair of electrodes, and means to interrupt the flow of current in said first circuit to develop a voltage sufficient to cause ionizing current flow between said first pair of electrodes.

2. A gas tube system comprising a gas-filled electron tube having a plurality of electrodes including a cathode, a source of voltage of amplitude less than that required to ionize the gas in said tube, an inductor, a circuit connecting said voltage source and said inductor in series between said cathode and another of said electrodes, a switch, a second circuit connecting said switch between said cathode and said another electrode, a work circuit including said voltage source connecting two of said electrodes including said cathode, and a capacitor connected between said last-named two electrodes.

3. A gas tube system comprising a gas-filled electron tube having three electrodes including an anode, a cathode, and a third electrode, a source of voltage of amplitude less than that required to ionize the tube gas, an inductor, a circuit including said voltage source and said inductor connecting said anode and said third electrode to ionize the gas in said tube in pulses, a load device, and a circuit separate from said first-named circuit connecting said anode to said cathode through said load device.

4. A system for operating a gas-filled tube of the type having a plurality of electrodes including a cathode electrode, said system comprising a source of voltage of amplitude less than that required to ionize the gas in said tube, a load device, a work circuit connecting two of said electrodes and including said voltage source and said load device, an inductor, a circuit including said voltage source and said inductor to generate a first voltage pulse of amplitude sufficient to ionize said tube gas, a circuit connecting said voltage pulse generating circuit between said cathode and another of said electrodes, a capacitor, and a circuit including said capacitor, said inductor, said cathode and said another electrode to generate pulses of amplitude sufficient to ionize said tube gas subsequent to said first voltage pulse.

6

5. A pulse energizing system for a gas-filled electron tube having electrodes including an anode, a cathode and an auxiliary electrode, said system comprising a source of voltage of amplitude less than that required to ionize the tube gas, an inductor, a capacitor, a pulse generating circuit connecting said auxiliary electrode and another of said electrodes and including said inductor and said voltage source, said pulse generating circuit including a switch operable to complete a circuit through said inductor in parallel with said source, said capacitor being connected in said pulse generating circuit in parallel with said switch, and a work circuit connecting said anode and said cathode through said source.

6. A pulse energizing system for a gas-filled electron tube having a plurality of electrodes, said system comprising a source of voltage less than that required to ionize the gas in said tube, an inductor, a circuit connecting said voltage source and said inductor in series between two of said electrodes, a switch, means normally biasing said switch closed, a second circuit connecting said inductor and said switch in series across said voltage source, current responsive switch 25

5 actuating means connected in said second circuit for opening said switch in response to current flow through said second circuit, a heater for one of said electrodes, and a circuit including said voltage source for supplying current to said heater.

10 7. Apparatus as defined in claim 6 wherein said switch actuating means and said switch comprise a relay having a pair of contacts connected in said second circuit and having an operating winding connected in said second circuit.

15 8. Apparatus as defined in claim 7 wherein said relay has an additional operating winding connected in circuit with two of said electrodes and said voltage source.
